(57) **CLAIM**

The ornamental design for a cue for billiards and other cue sports, as shown and described.

DESCRIPTION

FIG. 1 is a top front perspective view of a cue for billiards and other cue sports showing the claimed design;

FIG. 2 is a top rear perspective view thereof;

FIG. 3 is a top view thereof;

FIG. 4 is a bottom view thereof;

FIG. 5 is a side elevational view thereof;

FIG. 6 is a side elevational view thereof of the side opposite to the elevational view of FIG. 5;

FIG. 7 is a front elevational view thereof; and,

FIG. 8 is a rear elevational view thereof.

The broken line showing in the drawings is included for the purpose of illustrating unclaimed subject matter and forms no part of the claimed design.

1 Claim, 5 Drawing Sheets
